(57) **CLAIM**

The ornamental design for a pressure sensor, as shown and described.

DESCRIPTION

FIG. 1 is a front perspective view of a pressure sensor in accordance with the new design.

FIG. 2 is bottom perspective view thereof.

FIG. 3 is a front elevation view thereof.

FIG. 4 is a rear elevation view thereof.

FIG. 5 is a side elevation view thereof.

FIG. 6 is a side elevation view thereof, showing the side opposing that shown in FIG. 5.

FIG. 7 is a top elevation view thereof; and,

FIG. 8 is bottom elevation view thereof.

(Continued)

The broken lines shown in the drawings are only provided to illustrate the environment of the design and form no part of the claimed design.
